UNITED STATES PATENT OFFICE

126,891

DESIGN FOR A DRESS ENSEMBLE

Harry Langer, New York, N. Y.

Application March 26, 1941, Serial No. 99,884

Term of patent 3½ years

To all whom it may concern:

Be it known that I, Harry Langer, a citizen of the United States, residing in New York city, in the county of New York and State of New York, have invented a new, original, and ornamental Design for a Dress Ensemble, of which the following is a specification, reference being had to the accompanying drawings, forming partthereof.

I claim:

The ornamental design for a dress ensemble, substantially as shown.

HARRY LANGER.
